(57) CLAIM

The ornamental design for a worm composter, as shown and described.

DESCRIPTION

FIG. 1 is an exploded, perspective view of a worm composter according to my new design;

FIG. 2 is another exploded, perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof; and,

FIG. 10 is another perspective view thereof.

The broken lines showing of the worm composter are for the purpose of illustrating environmental structures of the worm composter and form no part of the claimed design.
